CLAIM

I claim the ornamental design for a cabinet, as shown and described.

DESCRIPTION

FIG. 1 is a perspective view of a cabinet showing the new and original design;

FIG. 2 is a front elevational view thereof;

FIG. 3 is a bottom plan view thereof;

FIG. 4 is a top plan view thereof;

FIG. 5 is a rear elevational view thereof; and,

FIG. 6 is a side elevational view with the opposite side view being a mirror image thereof.
